US0D1088116S

(12) **United States Design Patent** (10) **Patent No.:** **US D1,088,116 S**
(45) **Date of Patent:** **** Aug. 12, 2025**

(54) **FOLDER**

(71) Applicant: **IdeaStream Consumer Products, LLC**, Cleveland, OH (US)

(72) Inventor: **Eric Fitzgerald Klosky**, Chagrin Falls, OH (US)

(73) Assignee: **Ideastream Consumer Products, LLC**, Cleveland, OH (US)

(**) Term: **15 Years**

(21) Appl. No.: **29/772,320**

(22) Filed: **Mar. 1, 2021**

Related U.S. Application Data

(63) Continuation of application No. 29/679,723, filed on Feb. 8, 2019, now Pat. No. Des. 912,141, which is a continuation of application No. 29/580,307, filed on Oct. 7, 2016, now Pat. No. Des. 840,473, which is a continuation of application No. 29/510,697, filed on Dec. 2, 2014, now Pat. No. Des. 771,747, which is a continuation of application No. 29/462,107, filed on Jul. 31, 2013, now Pat. No. Des. 719,214, which is a continuation of application No. 29/388,222, filed on Mar. 25, 2011, now Pat. No. Des. 689,548.
